UNITED STATES PATENT OFFICE.

ERNST MOXTER, OF ST. LOUIS, MISSOURI.

ELECTRIC SOCKET.

Application filed November 22, 1923. Serial No. 676,406.

This invention relates generally to electrical-contact devices and, more particularly, to a certain new and useful improvement in sockets applicable for use in electrical service connections in houses, stores, offices, buildings, and the like for lamps, plugs, and other translating devices.

The chief objects of my present invention are to provide an electric socket which may be 10 readily manufactured and produced at low cost; to provide an electric socket comprising an insulation shell of readily separable and replaceable complementing sections; to provide an electric socket comprising an enclosing insulation shell equipped with readily detachable and replaceable electrical parts or fittings including lamp-receiving and contact and conducting members; to provide an electric socket comprising spaced conducting 20 members and conveniently operable means including an oscillatory lever for electrically connecting the conducting members; to provide an electric socket comprising separable insulation shell sections and electrical fittings 25 that may be readily, conveniently, and compactly assembled; and to improve generally upon and simplify the construction of electric contact devices of the type stated.

With the above and other objects in view, 30 my present invention resides in the novel features of form, construction, arrangement, and combination of parts hereinafter described and pointed out in the claim.

In the accompanying drawing,

35 Figure 1 is an enlarged vertical sectional view taken approximately through the center of an electric socket embodying my invention;

Figure 2 is a reduced similar view of the 40 socket taken approximately at right angles to Figure 1; and

Figure 3 is an elevational view of the socket.

Referring now more in detail and by reference characters to the accompanying drawing, which illustrates a preferred embodiment of my invention, A designates the body or shell of the socket, which externally has preferably the shape best seen in Figure 3. 45 Being generally cylindrical in form with a rounded upper-end wall, as at 1. The shell or body A is constructed of porcelain, hard rubber, or other suitable insulation material and is longitudinally divided to comprise a pair 50 of complementing separable sections 2, 3.

The body or shell section 3, best separately

seen in Figure 2, is internally hollowed or chambered annularly at its lower end, as at 4, to accommodate approximately half of a preferably metallic internally threaded tubular member 5 open at its lower end to receive and engage with the threaded base of a lamp or other analogous translating device, not shown, as will be well understood; and intermediate the upper end of its annular recess 60 4 and its upper end-wall portion 1, the shell-section 3 is additionally internally both longitudinally and transversely cut-away or recessed to accommodate and seat the additional various electrical fittings of the socket, 65 including the several contact and conducting members now to be described.

At its upper end, the tubular lamp-seating member 5 has an annular preferably integral inwardly presented flange, as at 6, riveted or 70 otherwise rigidly fixed both mechanically and electrically to which, as at 7, is a conducting-member preferably in the form of an angle 8 detachably, but firmly, secured or fastened to its seat within the shell section 3 by means 75 of a screw or the like 9 threaded through the wall of the shell-section 3 to engage the angle 8 and having its head (not shown) disposed below the peripheral plane of the shell-section in a recess, as at 10, provided for the 80 purpose in the cylindrical wall of the shell-section. By means of such screw 9 and angle 8 and the mechanical connection between angle 8 and lamp-seating member 5, the lamp-seating member 5 is also detachably, but firmly, held to its seat within the socket. 85

Seated flatwise within the shell-section 3 in spaced relation from the angle 8, is a transversely disposed second conducting-member 90 in the form preferably of a flat strip 11 likewise detachably, but firmly, secured or fastened to its seat by means of a screw 12 similarly threaded through the wall of the shell section to engage the strip 11 and having its head 12' also disposed below the peripheral 95 plane of the shell-section in a wall-recess 13. Disposed at one end intermediate the strip 11 and its seat and also engaged by the fastening-screw 12, as best seen in Figure 1, is a depending longitudinally-disposed contact or 100 switch-member in the form of a yielding preferably thin copper strip 14 suitably elongated for contacting engagement at its lower end with the conducting-angle 8 and suitably angularly bent intermediate its ends, as at 15, 105 for depressible engagement by means of a suitable insulation lever or toggle 16 project-

ing outwardly of the shell-section 3 through a suitable slot 17 provided for the purpose in the wall of the shell-section and detachably held to the wall of the shell-section for 5 manual oscillatory or rocking actuation by means of a through-pin 18 freely seated or disposed at its ends in oppositely-disposed grooves 19, 19, as best seen in Figures 1 and 2.

Also seated longitudinally within the shell-section 3 in suitably spaced relation from the yielding or spring switch-member 14 and insulated from the conducting-strip 11 by a wall 20 integral with the shell-section, as best seen in Figure 2, is a third conducting member 15 preferably in the form of a suitably elongated metallic strip 21 also detachably, but firmly, secured or fastened to its seat within the shell-section by means of a screw 22 similarly threaded through the wall of the shell-section 20 to engage the strip 21 and having its head, not shown, disposed below the peripheral plane of the shell-section. Adjacent the lower end 25 of the strip 21, the lamp-engaging member 5 and its flange 6 are interrupted or broken-away, as at 23, to accommodate the freely projecting end centrally at the base of member 5, as seen in Figures 1 and 2, of a transversely presented preferably copper or other conducting strip 24, which is riveted or otherwise rigidly fixed both mechanically and electrically at its other end, as at 25, to the lower end 30 of the conducting strip 21 and which provides a spring or yielding center contact for the lamp or other translating device inserted 35 in the tubular member 5.

Seated in the conducting-strips 11 and 21, are binding-screws 26, 26, that are adapted to electrically engage the terminal portions of electrical conductors 27, 27, which latter enter 40 the socket through a suitable preferably circular aperture 28 provided jointly by complementing semicircular recesses formed in the end-wall portions 1 of the socket sections 2 and 3.

45 The shell-section 2, which is adapted to fit at its edge upon the edge of the shell-section 3 to complete the socket A, is also internally hollowed or chambered annularly at its lower end to accommodate the other half of the lamp-engaging member 5, and adjacent its upper closed end-portion 1, shell-section 2 is also recessed, as at 29, to accommodate the 50 terminal portions of the lines 27, 27. Intermediate such upper recess 29 and its lower recess for accommodating the lamp-receiving 55 member 5, the shell-section 2 is substantially solid, as at 30, with merely such surface recesses that may be required to accommodate any projecting or protruding portions of the 60 several described fittings mounted upon the co-operating shell-section 3. Immediately above said lower recess, however, the shell-section 2 is formed with a projecting preferably integral portion 31 which, when the 65 shell-sections 2 and 3 are in complementing

shell-forming relation, as illustrated in Figure 3, is adapted to extend into the shell-section 3 and bridge-cross and thereby close and insulate the upper end of lamp-receiving member 5 over the depending center-contact 70 providing-end of the strip 24.

The shell-sections 2 and 3 being in edge-abutting shell forming relation, as in Figure 3, a suitably elongated screw 32 is suitably threaded through the wall of section 3 to engage 75 the solid portion 30 of section 2, the screw 32 having its head also disposed below the peripheral plane of the socket in a recess 33 provided for the purpose and the shell-sections 2 and 3 being thereby firmly secured 80 detachably together in complementing shell completing relation.

As so constructed, it will be evident that the shell-section 2, which is substantially a cover or enclosing-member for the several fittings 45 carried by the complementing shell-section 3, may be readily detached from the section 3, when the several described fittings of section 3 are fully exposed and repairs or replacements of any of such parts may be conveniently and inexpensively made.

90 My new socket is simple, inexpensive, and compact in form and construction and exceedingly efficient in the performance of its intended functions.

95 I may add that normally, with the shell-sections 2 and 3 in shell-completing relation as illustrated in Figure 3 and with the several enclosed fittings of such sections in the relation illustrated in Figure 1, the switch or contact-member 14 is at its free lower end yieldingly spaced from the stationary contact or conducting-member 8. On rocking actuation 100 of the lever 16, however, the contact-strip 14 will be depressed into contacting electrical engagement with the conducting-member or angle 8 and the wall of the tubular lamp-receiving member 5, when the inserted lamp or the like seated in the member 5 and electrically engaging both the member 5 and the 110 center contact 24, will be energized.

115 I am aware that changes in the form, construction, arrangement, and combination of the several parts of my new socket may be made and substituted for those herein shown and described without departing from the 120 nature and principle of my invention.

Having thus described my invention, what I claim and desire to secure by Letters Patent is:

125 In an electric socket, in combination, an insulation shell, a pair of conductors seated within and disposed in spaced relation longitudinally of the shell, said conductors being also disposed in parallel relation and located, 130 transversely of the shell, in different planes, separate screw members projecting from the exterior inwardly through the wall of the shell and engaging the respective conductors for securing the same to their seats, a switch-

member disposed longitudinally of the shell and having one end secured in electrical engagement with one of said conductors by one of said screw-members, the switch-member having its other end normally in spaced yielding relation to the other conductor, and a lever mounted for oscillation upon the shell

for depressing the free end of the switch-member into electrical engagement with said other conductor.

10

In testimony whereof, I have signed my name to this specification.

ERNST MOXTER.
